UNITED STATES PATENT OFFICE.

LIPA POLINKOWSKY, OF HYDE PARK, LONDON, ENGLAND, ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

1,372,448.

Specification of Letters Patent. Patented Mar. 22, 1921.

Application filed August 27, 1918. Serial No. 251,604.

To all whom it may concern:

Be it known that I, LIPA POLINKOWSKY, a citizen of Russia, residing at 70 Westbourne Terrace, Hyde Park, London, W., England, have invented certain new and useful Improvements in Machine-Switching Telephone-Exchange Systems, of which the following is a full, clear, concise, and exact description.

10 This invention relates to machine switching telephone exchange systems and more particularly to machine switching telephone systems wherein calls are to be extended by an "A" operator at a manual common battery exchange to subscribers over a semi-automatic "B" board.

20 A particular feature provides that apportioning means is brought into action which automatically brings the selection initiated on the "B" board under the control of the plug inserted in the jack of the "A" board, and also provides that the connection is automatically released on withdrawing the plug from the jack on the outgoing end of 25 the trunk line.

In systems of the above character the "B" operator's position is provided with a set of number keys, which the operator depresses according to the designation of the wanted 30 number, register sets which take positions corresponding to the depressed number keys and assignment keys individual to the trunk lines whereby the depression of an assignment key causes the automatic connection of 35 the incoming end of the trunk line with a free register set. The "B" operator after receiving from the "A" operator over an order wire the number of the wanted subscriber has in a regular connection only to 40 depress the assignment key of a free trunk line, give the "A" operator the number of such trunk line and depress the number keys.

45 A further feature of the invention therefore provides that the selection is initiated on the "B" board and is partially progressed disregarding whether the plug has been brought into the jack on the "A" board or not, but the completion of the selection is 50 made automatically dependent upon the insertion of the plug into the jack on the outgoing end of the trunk line.

In the operation of systems of the above character it is desirable that the semi-automatic "B" operator be able to restore the

switches at any time during the progress of 55 the selection, even though the "A" operator has plugged into the jack of the assigned trunk line. The necessity for this may arise from several causes, as when she wishes to repeat the number of the wanted line on her 60 keyboard, or when she observes from the signals on her position that the selection is not progressing.

Another feature of the invention therefore relates to an arrangement which enables the "B" operator to force the release 65 of the switches disregarding the condition of the outgoing end of the trunk line, *i. e.*, whether a plug has been inserted in the jack.

Still another feature of the invention and 70 one related to the last named is the provision of an improved arrangement of circuits and apparatus by which the "B" operator can force the release of the switches in depressing a common key on her position and 75 the assignment key individual to the trunk line which is otherwise used to initiate the connection of the trunk line with a free register set.

Should the "B" operator when desirous 80 of forcing the release of the switches maintain the assignment key depressed for a time longer than the switches need for restoration to their position of rest, the trunk line may again be connected with a register set. 85

Still another feature of the invention relating to the features above-mentioned provides an arrangement of circuits and apparatus for the delaying of the forced release until the "B" operator has freed the assignment key. 90

A further feature of the invention provides that apportioning means are brought into action whereby if the wanted line is found busy the switch on the incoming end of the trunk line is held in a position in which a flash signal is transferred from the incoming to the outgoing end of the trunk line through the medium of a relay locally operated in a circuit over a common interrupter. 100

As the work of an operator on a semi-automatic "B" position is simpler than the work of an "A" operator at a semi-automatic exchange, it becomes desirable to add 105 register sets to the semi-automatic "B" positions in case the semi-automatic "B" operator is delayed through registers being

tied up on the progress of selections. This is especially important on positions on which orders are given to the semi-automatic "B" operators over order wires.

5 Another feature of the invention is the provision of circuits and apparatus for the connection of a third register set on the semi-automatic "B" operator's position with the set of number keys and the connection of 10 the incoming end of a trunk line, on the depression of the assignment key individual to the trunk line with one of the three register sets.

A further feature of the invention relating to the feature above-mentioned involves 15 circuits and apparatus by which preference is given to one of the register sets and when this is busy to the second register set, and when this second is engaged to the third 20 register set of the "B" position, whereby a register set once connected with a trunk line remains engaged, regardless of whether or not the other registers become free, and whereby also the three register sets are made 25 busy as long as one of them is connected with the set of number keys.

Figure 1 shows the connecting plug on a manual common battery board of the well known type and the outgoing end of a trunk 30 to a semi-automatic exchange.

Fig. 1^a shows the incoming end of a trunk connected to a first group selector which has access to the registers of a "B" operator's position.

35 Figs. 2 and 3 show the arrangement of three register sets, the detailed arrangement of one of the registers only being shown however, the other two registers being indicated only in so far as is necessary 40 for the understanding of the system.

Fig. 3 also shows the keyboard for use in connection with the three register sets shown in Figs. 2 and 3.

Fig. 3^a shows a set of counting relays for 45 controlling selection.

Fig. 4 shows a second group selector and Fig. 4^a shows a final selector. The system will be best understood from a description of the operation thereof.

50 When a connection is to be extended from the manual "A" board to the semi-automatic exchange, the "A" operator communicates with the semi-automatic "B" operator over an order-wire 200 by depressing an order 55 wire key 201, which connects the wires 202 of her telephone with the "B" operator's telephone 301 indicated in Fig. 2. The "B" operator responds with the number of the selected free trunk line and depresses the 60 assignment key 203 of this trunk line. Relay 204 is thereby energized in a circuit over right hand contact of key 203 and sequence switch contact 205 top. The magnet of the sequence switch 206 individual to the first 65 group selector on the incoming end of the

trunk is thereby energized in a circuit over sequence switch contact 207 bottom, front contact of relay 204 and sequence switch contact 208 bottom. The sequence switch 206 starts from position 1 and moves under 70 the control of its local contact 209 into its position 2, in which the searching sequence switch 251 also individual to this group selector is energized in a circuit over contact 211 top of sequence switch 206 and back 75 contact of test relay 212.

During the time sequence switch 206 is in its position 2 and sequence switch 251 is searching for connection with a free register, the guard lamp 218 of the trunk line is 80 connected in a circuit over sequence switch contact 217 top to an interrupter 219, and displays a flashing signal, whereas the busy lamp 216 is connected over sequence switch contact 221 bottom and is lighted. Sequence 85 switch 251 starts from the position in which it was left on the previous call and with the help of the test relay 213 searches for a connection with a free register of the operator's position. Contact 252 top of this 90 sequence switch is closed for a short time between each position in which the sequence switch 251 can obtain a connection with a register. The semi-automatic "B" operator's position is provided with three 95 register sets designated A, B, and C, the controlling sequence switches of which are diagrammatically indicated in Fig. 2. The sequence switch 251 can obtain in positions 1, 4, 7 or 10 connection with the "A" register, in positions 2, 5, 8 or 11 with the "B" register, and in positions 3, 6, 9 or 12 with the C register. Privilege, as will be described, is given to the A register. When this is engaged with a trunk line the other 100 registers of the position are isolated until the number keys have been depressed. The B register can then be taken, and during the time the A and B registers are engaged after the number keys have been depressed 110 a second time, the C register is available. A connection once established with one register cannot be disturbed through another register becoming free.

Assuming that the three registers are free 115 and that the sequence switch 251 had started from position 6; before reaching position 7 the right hand high resistance winding of the test relay 213 is temporarily connected to ground over the sequence switch contact 120 252 top, and relay 213 is energized in a circuit over contact 214 bottom of sequence switch 206, contact 255 bottom of sequence switch 251, common wire 390, right hand winding of relay 311, Fig. 2, relay 312, contact 313 top of sequence switch 310 individual to the A register, back contact of relay 349 individual to the C register, and contact 335 of sequence switch 330 individual to the B register. The circuit clos- 125 130

ing positions of sequence switch contact 252 are so arranged that this contact is closed in its half positions for an interval during the closure of contacts 255, 258 and 259, 5 sufficient to permit the energization of test relay 213. Relay 213 connects over its front contact its left hand low resistance winding and the second test relay 212 in parallel to its high resistance winding before contact 10 252 is opened. A busy potential is created on common wire 390 and relays 212, 311 and 312 are energized. The circuit for sequence switch 251 is opened on back contact of relay 212 and this sequence switch is arrested in position 7 as soon as its local contact 254 is also opened. Sequence switch 206 is now energized in a circuit over sequence-switch contact 215 top and front contact of relay 212, starts from its position 2 15 and moves over position 3 into position 5, in which the busy lamp 216 associated with the trunk is connected in circuit over sequence switch contact 217 bottom and the interrupter 219. The lamp 216 displays a flashing signal, indicating the connection with a register, which is now kept busy over sequence switch contact 221 top. The test relays 213 and 212 are disconnected. The guard lamp 218 is disconnected from the 20 interrupter 219 and connected over sequence switch contact 228 bottom with the back contact of relay 229.

Relay 311 provides over its right hand front contact and sequence switch contact 314 bottom a starting circuit for sequence switch 310 which moves from position 1 into position 5. Over the left front contact of relay 311 and sequence switch contact 315, the left hand high resistance winding of this 25 relay is connected in series with its right hand winding. Relay 312 when energized provides the connection of relay 316 in series with relay 311 and in parallel to the test relays 213, 212. Relay 316 is thereby 30 energized and connects over its front contact battery direct to the winding of relay 312, so that the high resistance winding of relay 311 remains still shunted by the winding of the low resistance relay 312, so preventing the deenergization of the marginal test relays 213 and 212, in case sequence switch contact 313 is opened before sequence switch 206 reaches its position 4. When 35 sequence switch 206 is in position 4 the direct ground connected over sequence switch contact 221 causes the short-circuiting of relay 316, which is deenergized and leaves the left hand high resistance winding of relay 311 to maintain its energization. Sequence 40 switch 310 in reaching position 5 tests whether the number keys of the operator's position are free. If this is the case relay 401, Fig. 3, is deenergized, the energization of sequence switch 310 is maintained over 45 back contact of relay 401 conductor 481 and

sequence switch contact 317 top, and the sequence switch moves into position 6 in which the magnetic clutches 402 of the number keys 403 are energized in a circuit over the wipeout key 404 conductor 482 and sequence switch contact 318 top. 70

Seeing the flash of the busy lamp 216, the operator depresses on the number keys the number wanted and after one key in each row is depressed a circuit is closed for relay 401 over the right hand contacts of the depressed 10000's, 1000's, 100's, 10's and units keys and relay 401 is energized. Sequence switch 310 is energized in a circuit over front contact of relay 401 conductor 483 and sequence switch contact 319 top. This sequence switch starts from position 6 and moves into position 7 in which contact 321 is closed, connecting battery to contact 333 of sequence switch 330 so that from this moment the B register is made free and can be connected with a trunk line for a following call. The left hand winding of relay 349 is thereby also energized but this remains, in the present state of the circuit, without effect on the C register. 80

In parallel to the winding of relay 401 a circuit over conductor 484 sequence switch contact 328 conductor 485 and the back contacts of the test relays 405, 406, 407, 408, 409, connects and energizes the respective magnets of the registers 411, 412, 413, 414, and 415. This circuit also contains the winding of a common relay 400 which is thereby energized. The registers 411, 412, 413, 414, 415 start to rotate from the positions in which they have been left on the previous call and during their rotation the corresponding test relays search the depressed key in the corresponding rows of the number keys. If, for example, key 1 in the 10000's row has been depressed, the relay 405 will be energized in a circuit over contact 416 bottom of register 411 and the left hand contact of key 1 as soon as this register reaches position 1. Register 411 is then disconnected on back contact of relay 405 and is held in position 1. After all registers have been so arrested in positions corresponding to the depressed number keys, relay 400 is deenergized. Sequence switch 310 is now energized in a circuit over its contact 317 bottom conductor 486 and back contact of relay 400 and starts from position 7, moving into position 10. As soon as sequence 95 switch 310 leaves position 7 and contact 318 is opened, the magnetic clutches 402 are disconnected and the number keys are made free so that relay 401 also becomes deenergized. 100

In position 10 of sequence switch 310 the fundamental circuit is closed for the first group selector containing the stepping relay 322 and relay 204, from sequence switch contact 323 bottom, conductor 487 back con- 115 120 125 130

tact of the zero counting relay 422, stepping relay 322, conductor 391 sequence switch contact 253 bottom sequence switch contact 222 top relay 204. Both relays 322 and 204 are energized. Relay 322 provides the circuit for the energization of the counting relay according to the position of the registers 411 and 412. Register 411 serves only to control translation for the odd and even 10 initial digit of the number of the desired line the capacity of the exchange being assumed to be 20000 lines. Assuming that the number wanted was 11319, the counting relay 424 is energized in a circuit over front contact of relay 322, sequence switch contact 363 top, conductor 488, sequence switch contact 431 top of register 412, contact 417 bottom of register 411, conductor 471, and back contact of relay 423. Relay 424 provides a 20 holding circuit over winding of relay 423, front contact of relay 424 conductor 489 and sequence switch contact 318 bottom. Relay 423 remains, however, deenergized, being short-circuited at the front contact of relay 422.

The energization of the relay 204 causes over its front contact the operation of sequence switch 206, and this sequence switch starts from its position 5 and moves into its 30 position 6 in which the magnet 223 of the trip spindle is energized in a circuit over sequence switch contact 224 bottom and front contact of relay 204. The trip spindle starts to rotate and between each position a short-circuiting of relay 322 takes place in the well known manner, on the contact 225 top of the trip spindle over sequence switch contact 226 bottom of the sequence switch 206. As soon as the stepping relay 322 is deenergized relay 423 is energized, disconnects relay 424 from wire 471 and connects this wire with the winding of relay 425. When after opening the short-circuit on the trip spindle the stepping relay 322 is again energized, relay 425 is operated in the described circuit and when the stepping relay is again short-circuited relays 422 and 426 are energized in series with relay 425. The fundamental circuit is opened on the back 45 contact of relay 422, and sequence switch 310 is energized in a circuit over front contact of relay 426 conductor 490 and sequence switch contact 319 bottom. Sequence switch 310 starts from its position 10 and moves into its position 12. In leaving position 10 the ground is disconnected at sequence switch contact 323 bottom and the fundamental circuit is again prepared this time over the top of this sequence switch contact 55 323, conductor 393 and sequence switch contact 256. The holding circuit of the counting relays is opened on sequence switch contact 318 so that the current is first reduced through introduction of resistance 327, and the counting relays are then deenergized.

The purpose of resistance 327 is to reduce the sparking on this sequence switch contact.

As soon as the short-circuiting contact on the trip spindle is also opened, relay 204 is deenergized and sequence switch 206 is energized in a circuit over sequence switch contact 215 bottom, back contact of relay 204 and sequence switch contact 207 bottom. Sequence switch 206 starts from position 6 and moves into position 7 in which the test 75 relay 213 is connected with the test brush 227 of the first group selector. Relay 204 is again energized in a circuit over contact 226 top of sequence switch 206, contact 257 of sequence switch 251, conductor 392 sequence switch contact 324 of sequence switch 310 and front contact of relay 311. In position 7 of sequence switch 206 a circuit is also closed over back contact of relay 212 and sequence switch contact 211 bottom to the 85 power magnet 240 of the brush carriage, and the carriage is moved in the well known manner with its appropriate brushes selected and released by the set position of the trip spindle making contact with the terminals of the selected terminal row. Relay 90 213 searches for a free trunk line to a second group selector and upon finding such a line its right hand winding is energized in a circuit over sequence switch contact 205 bottom 95 and over sequence switch contact 214 top, test brush 227, contact 501 of sequence switch 510 individual to the free second group selector and right hand winding of relay 502.

The left hand low resistance winding of 100 relay 213 is brought into circuit over its front contact together with relay 212 in parallel to the high resistance winding of relay 213. The test terminal of the second group selector is so made busy and relays 105 212 and 502 are energized. Sequence switch 206 is now energized in a circuit over front contact of relay 212 and sequence switch contact 215 top. The holding magnet 245 of the brush carriage is thereby also 110 energized in a parallel circuit containing sequence switch contact 244 bottom. The brush carriage is arrested and the sequence switch 206 starts from position 7 and moves over position 8 into position 9 by means of 115 a circuit closed through upper contact 215 and the front contact of relay 212. The progress of the selection is now made dependent on whether the operator has plugged into the jack on the outgoing end of the 120 trunk. As long as this is not the case the guard lamp 218 remains lighted in a circuit over sequence switch contact 228 bottom and back contact of relay 229.

If or after the plug is inserted relay 125 230 on the outgoing end of the trunk line and supervisory relay 231 in the cord of the A operator's position are energized in a circuit over the sleeve of the connecting plug, both windings of relay 232 are brought over 130

the front contacts of relay 230, in connection with both wires of the trunk line 270. Release relay 233 which is connected with its high and low resistance windings together with a retardation coil 234 in bridge to the incoming end of the trunk is now energized in a metallic circuit, and causes over its front contact the energization in a local circuit of relay 229. The sequence switch 206 having reached position 9 is now energized in a circuit over front contact of relay 229, back contact of supervisory relay 235, sequence switch contact 210 bottom, and moves into position 10. The fundamental circuit 15 is now extended over sequence switch contacts 236 and 237 bottom and the brushes 238 and 239 of the first group selector to the fundamental circuit of the second group selector which is closed on sequence switch 20 contact 503 bottom to relay 504 and on sequence switch contact 505 bottom to ground. Relays 504 and 322 are energized. The circuit for the counting relays is again closed over front contact of relay 322, sequence 25 switch contact 363 bottom, conductor 491 contact 441 bottom of register 413, contact 432 bottom of register 412, wire 473, back contact of relay 427 to winding of counting relay 428. Relay 428 is energized and provides a holding circuit for its winding over its front contact and winding of relay 427. Relay 504 when energized provides a circuit over its front contact and sequence switch contact 506 top for the energization of sequence 30 switch 510 which starts from position 1 and under the control of its local contact 511 moves into position 2 in which the left hand high resistance winding of relay 502 is brought in the circuit of the test terminal 227 after sequence switch contact 501 is opened. The magnet 520 of the trip spindle is in this position of the sequence switch energized in a circuit over the sequence switch contact 507 bottom and front contact of relay 504. The trip spindle moves and provides again the short-circuitings on the fundamental circuit over its contact 508 top and sequence switch contact 509 top. As soon as stepping relay 322 is deenergized 45 relay 427 becomes energized, disconnects the winding of relay 428 and connects wire 473 with winding of relay 429. The counting relays are thus energized in succession until on the last short-circuiting of the trip spindle relays 422 and 426 are energized and the fundamental circuit is again opened. Sequence switch 310 is again energized in the circuit described and moves from position 12 into position 14. After leaving position 12 the holding circuit for the counting relays is again temporarily opened on sequence switch contacts 318 and 326 and the counting relays are deenergized. The fundamental circuit is maintained opened 60 on sequence switch contact 323 until sequence

switch 310 reaches position 14. The duration of this opening of the fundamental circuit on the register is so selected that after the short-circuiting contact on the trip spindle of the second group selector is opened, relay 504 is deenergized, sequence switch 510 is started from position 2 in a circuit over back contact of relay 504 and sequence switch contact 514 bottom, and the fundamental circuit is opened on contacts 503 and 505 of the sequence switch 510 before the circuit is again closed on the register. Sequence switch 510 moves into position 3 in which the power magnet 530 of the brush carriage is energized in a circuit over back contact of test relay 512 and sequence switch contact 515, and the brushes of the carriage are moved along the terminals of the final selector in the terminal row which corresponds with the position of the trip spindle, whereby relay 513 which is connected with the test brush 527 tests for a free final selector. When such a terminal is found, the left hand high resistance winding of relay 513 is energized in a circuit containing right hand front contact of relay 502, sequence switch contact 516 top, the test brush 527, contacts 540 and 541 of the sequence switch 550 individual to the free final selector and the right hand winding of relay 542. The right hand low resistance winding of relay 513 is brought in parallel to its high resistance winding in a circuit over its front contact, sequence switch contact 517 and winding of relay 512, and the test terminal of the final is so made busy, and relays 512 and 542 are energized. The sequence switch 510 of the second group selector is now energized in a circuit over front contact of relay 512 and sequence switch contact 514 top and, the holding magnet 525 is connected in parallel to the sequence switch over sequence switch contact 506 bottom. The brush carriage is arrested and sequence switch 510 starts from position 3 and moves over positions 4 and 5 into position 6 in which the fundamental circuit is extended to the final over the sequence switch contacts 518 and 519 and the brushes of the second group selectors 538 and 539, whereby the fundamental circuit is closed on contact 543 top of sequence switch 550 to relay 544 and over sequence switch contact 545 top to ground. The stepping relay 322 and relay 544 on the final selector are energized. The circuit for the counting relays is now again closed on the register over front contact of relay 322, sequence switch contact 325 bottom, conductor 492 contact 451 bottom of register 414, conductor 471, back contact of relay 423 to winding of relay 424, which is energized. Relay 544 causes the energization of sequence switch 550 in a circuit over sequence

switch contact 556 top and front contact of relay 544. The sequence switch 550 starts from position 1 and moves under the control of its local contact 551 into position 2 in 5 which the trip spindle magnet 560 is energized in a circuit over sequence switch contact 557 bottom and front contact of relay 544. The trip spindle starts and provides on its contact 558 top and over sequence 10 switch contact 559 top, short-circuitings in the fundamental circuit and the counting relays are again operated in succession as hereinbefore described. After relays 422 and 426 are again energized the fundamental 15 circuit is again opened and sequence switch 310 is energized and moves from position 14 into position 16. The holding circuit for the counting relays is again temporarily opened and the fundamental 20 circuit is held opened as described until sequence switch 310 reaches position 16, whereby the opening of the fundamental circuit is of such duration that after the short-circuiting contact 558 on the final is 25 opened, relay 544 is deenergized and sequence switch 550 energized in a circuit over back contact of relay 544 and sequence switch contact 561 top, and starts from position 2, moving into position 5. The sequence switch contact 557 is opened before 30 the fundamental circuit is again closed on the register and on the other hand the energization of relay 544 takes place before sequence switch 550 reaches position 5, in 35 which position the power magnet 570 of the brush carriage is energized in a circuit over front contact of relay 544 and sequence switch contact 562 top. The carriage moves with the brushes along the terminal row 40 which has been selected by the position of the trip spindle.

When the fundamental circuit is again closed on contact 323 in position 16 of sequence switch 310, the counting circuit is again established over front contact of stepping relay 322, sequence switch contact 325 top, conductor 493, contact 442 top, of register 413, contact 469 bottom, back contact of relay 478 and winding of counting relay 479, so that relay 479 is energized. When the brush carriage during its rotation provides the short-circuiting on the fundamental circuit over its contact 563 top and sequence switch contact 559 top the stepping relay 322 controls in the manner described the operation in succession of the counting relays until relays 422 and 426 are energized, when the fundamental circuit is opened and sequence switch 310 is energized, starts from position 16 and returns to its position of rest. In leaving position 16 the sequence switch 310 provides the opening of the holding circuit for the counting relays, as well as the fundamental circuit, as described. In opening sequence switch con-

tact 315 relay 311 is deenergized and closes at its back contact a circuit enabling the sequence switch 310 to remain energized in position 18 over its contact 314 top, and to move into its position 1. The A register 70 is now free to be used for another connection. The opening of the right hand front contact of relay 311 causes the deenergization of relay 204 which provides over its back contact a circuit for sequence switch 75 206, as described, so that this sequence switch starts from position 10 and moves into position 12 in which relay 204 is again energized in a circuit over sequence switch contact 210 top, back contact of relay 235 80 and front contact of relay 229. The busy lamp 216 is now disconnected from the interrupter 219 and connected over sequence switch contact 221 to ground displaying a busy signal during the connection. 85

Returning to the operation of the final selector, its relay 544 becomes deenergized after the opening of the fundamental circuit as soon as contact 563 top of the brush carriage is opened. Sequence switch 550 is again energized in the circuit over back contact of relay 544, as described. In parallel to the sequence switch the holding magnet 580 is connected over sequence switch contact 581. The brush carriage is arrested on the terminals of the wanted line and the sequence switch 550 starts from position 5 and moves into position 10. By the opening of sequence switch contacts 543 and 545 the fundamental circuit is now disconnected on the final selector. The deenergization of relay 311 on the register is controlled on the sequence switch contact 315 of register 310 so that the fundamental circuit on the final selector is opened before sequence switch 206 reaches position 12 in which the brushes 238 and 239 are connected over the sequence switch contacts 236 and 237 respectively with the current supply bridge containing the supervisory relay 235 and retardation coil 241. When sequence switch 550 leaves position 6 the left hand high resistance winding of relay 542 is brought into the circuit of the test terminal 527 as soon as contact 541 is opened. When sequence switch 550 of the final selector passes position 8 a test is made on the wanted subscriber's line through a temporary closure of sequence switch contact 564 to ground, so that if the line is free the right hand winding of the test relay 573 is energized in a circuit containing sequence switch contact 564, the test brush 567, and the cut-off relay 568 of the wanted line. The left hand low resistance winding of relay 573 is brought in parallel to its high resistance winding over its front contact, winding of second test relay 572 and front contact of relay 542. The test terminal of the wanted line is thus made busy, and the relays 572 and 130

568 are energized. When sequence switch 550 reaches position 10 its energization is maintained in a circuit over its contact 569 bottom and front contact of relay 572, and 5 the sequence switch moves over positions 10 and 11 into position 12 in which the ringing current supply and the ringing relay 574 are connected over sequence switch contacts 575 and 576 respectively with the wanted 10 line.

In positions 8 to 11 of the sequence switch 550 a resistance 577 is brought in bridge to the line and relay 235 is energized in a metallic circuit over the brushes of the first 15 and second group selectors and the sequence switch contacts 545 bottom and 578 top of the final selector. The circuit described for relay 204 is now opened on back contact of relay 235 and the sequence switch 206 is again energized over the back contact of 20 relay 204. This sequence switch starts from position 12 and moves into its position 13. As soon as sequence switch 550 of the final passes position 11 the resistance 577 is disconnected and relay 235 is deenergized. 25 Sequence switch 206 is now energized in a circuit over its contact 210 bottom, back contact of relay 235 and front contact of relay 229, the sequence switch starts from position 30 13 and moves into position 14 in which relay 204 is again energized over back contact of relay 235 as described. When the called subscriber replies by removing the receiver from the switch hook, ringing relay 574 on the final selector is energized over the called subscriber line and causes the energization of sequence switch 550 in a circuit over its contact 569 top and front contact of relay 574. The sequence switch 550 35 starts from position 12 and moves into position 13 in which the ringing current supply is disconnected on the sequence switch contacts 575 and 576 and through connection with the wanted line is made on the top of these contacts. Relay 235 is now again energized and relay 204 is deenergized, causing again over its back contact, as described, the energization of sequence switch 206, which starts from position 14 and moves into 40 position 15, in which position the sequence switch remains during the conversation. The right hand high resistance winding of relay 233 is now short-circuited over sequence switch contact 242 bottom, back contact of relay 204 and sequence switch contact 207 top. Relay 232 on the outgoing end of the trunk is now energized and provides on its front contact the short-circuiting of supervisory relay 231 on the cord. 45 The time the short-circuiting contact 563 of the brush carriage of the final selector is closed is not in all cases the same, the final selector being arranged for 200 subscriber lines, the terminals of the odd and even 50 hundred are separated from one another and

when the brush carriage moves over this space the short-circuiting on its contact 563 is of comparatively long duration. To control the moment when sequence switch 206 shall be started from position 10 an arrangement is made over a contact 443 of the 100's registers 413 and a contact 461 of the units register 415, so that if according to the depressed number keys the 100's register is in one of its positions 1-3-5-7-9 and 70 the units register is in its position 0, which corresponds to the first terminal in the second half of the terminal row of a final selector, relay 311 is maintained energized after sequence switch 310 leaves position 16 80 in a circuit over conductor 494 contact 443 of register 413, contact 461 of register 415 conductor 495 and sequence switch contact 313 bottom, until the sequence switch 310 leaves its position 17. The deenergization 85 of relay 311 and in consequence relay 204 and the starting of the sequence switch 206 is therefore delayed for a corresponding length of time.

When the conversation is finished and the 90 called subscriber replaces his receiver on the hook, relay 235 is deenergized and in consequence relay 204 energized. The short-circuit of the high resistance winding of relay 233 is opened and relay 232 is deenergized. Relay 232 opens the short-circuit of relay 231 which is again energized and the clearing-out signal is displayed before the A operator. When the A operator receives the clearing-out signals from both parties 95 and disconnects by withdrawing the plugs from the jacks, relay 233 is deenergized and in consequence relay 229. Motor magnet of sequence switch 206 is now energized in a circuit over sequence switch contact 208 top 100 and back contact of relay 229 and the sequence switch moves from position 15 into position 18. In leaving position 15 the brushes of the first group selector are isolated on sequence switch contacts 214, 236 and 110 237, relay 502 on the second group selector is deenergized and sequence switch 510 is energized in a circuit over its contact 521 top and the back contact of relay 502, and sequence switch 510 starts from position 6 and 115 moves into position 10. From position 10 said sequence switch advances to position 17 by means of a circuit closed over the back contact of relay 504 and the lower contact 514. 120

After sequence switch 510 leaves position 16, the circuit over the test brush 527 is opened on sequence switch contact 517 and the relay 542 on the final selector is deenergized. Sequence switch 550 is thereby energized over its contact 556 bottom and back contact of relay 542, starts from position 13 and moves into position 15; finding there the relay 544 deenergized the sequence switch maintains its energization over sequence 130

switch contact 561 top, and back contact of relay 544. Sequence switch 550 moves then over position 15. In position 16 the energization of this sequence switch is again maintained over its contact 556 bottom and back contact of relay 542 so that the sequence switch moves into position 18.

When sequence switch 206 reaches position 18 the power magnet 240 of the first group selector is again energized in the circuit over sequence switch contact 211 bottom and back contact of relay 212, and the brush carriage is restored to its position of rest, whereby as soon as the home contact 243 is closed relay 212 is energized in a circuit over home contact 243, sequence switch contact 244 top and the holding magnet 245, the brush carriage is arrested, and the sequence switch 206 is again energized in a circuit over its contact 215 top and front contact of relay 212. The sequence switch 206 moves from position 18 into position 1, sequence switch contact 221 is opened and lamp 216 extinguished.

25 When the sequence switch 510 of the second group selector reaches its position 17 the power magnet 530 is again energized in a circuit over sequence switch contact 515 and back contact of relay 512, and the brush carriage is restored to its position of rest. After the home contact 523 is closed relay 512 is energized in a circuit over home contact 523 and sequence switch contact 524. The power magnet is disconnected and the sequence switch 510 is again energized over its contact 514 top and front contact of relay 512. In parallel to the sequence switch is thereby connected the holding magnet 525 over sequence switch contact 506 bottom. 40 The brush carriage is arrested and the sequence switch moves from position 17 into position 18, in which the trip spindle magnet 520 is energized in a circuit over sequence switch contact 507 top and trip spindle contact 508 bottom, also relay 504 is maintained in its position energized over sequence switch contact 509 bottom and trip spindle contact 508 bottom. The trip spindle returns to its position of rest. In 45 opening of contact 508 relay 504 is deenergized, the sequence switch 510 is again energized over its contact 514 bottom and back contact of relay 504, starts from position 18 and moves into position 1.

50 When the sequence switch 550 of the final selector reaches position 18 the final selector power magnet 570 is energized in a circuit over sequence switch contact 561 bottom and back contact of relay 544, and the brush carriage is returned to its position of rest in which the home contact 563 bottom is closed and relay 544 is energized in a circuit over sequence switch contact 559 bottom and the home contact 563 of the final brush carriage. The power magnet 570 is discon-

nected and sequence switch 550 is again energized in a circuit over its contact 556 top and front contact of relay 544. In parallel to the sequence switch 550 is connected the holding magnet 580 over sequence switch 70 contact 581 bottom, the brush carriage is arrested and the sequence switch is started from position 18 and moved into position 1.

If the wanted line has been found busy and test relay 573, when the sequence switch 550 passes position 8, was not energized the sequence switch 550 is arrested in position 10 in which the power magnet 570 is energized in a circuit over sequence switch contact 561 bottom and back contact of relay 544, and the brush carriage is moved into the position of rest. When the home contact 563 of the brush carriage is closed, relay 544 is energized in the circuit over sequence switch contact 559 bottom and over contact of the brush carriage 563 bottom, power magnet 570 is disconnected, and the sequence switch 550 and the holding magnet 580 are energized over the front contact of relay 544 and sequence switch 80 contact 556 top. The brush carriage is arrested and sequence switch 550 is moved into position 11. Resistance 577 remains connected over sequence switch contacts 545 and 578 in bridge to the line and relay 235 is 85 continuously energized during the time the brush carriage is restored to its position of rest and also when the sequence switch 550 remains in position 11. The sequence switch 206 individual to the first group selector is 90 held in position 13. Relay 204 is in this position connected over sequence switch contact 222 bottom to a common interrupter 246 and each time the interrupter is closed relay 204 is energized and the high resistance winding of relay 233 is short-circuited over sequence switch contact 207 top, front contact of relay 204 and sequence switch contact 242 top. Relay 232 is thereby each time 95 energized and in short-circuiting on its front contact relay 231 causes the extinguishing of the supervisory lamp on the cord. A busy flash signal is so transmitted to the operator who informs the calling party and disconnects by withdrawing the plug from 100 the jack. Relay 233 is thereby deenergized and in consequence relay 229. Sequence switch 206 is energized over its contact 208 top and back contact of relay 229, starts from its position 13 and moves over its positions 14 and 15 into position 18, in which the brush carriage is restored and the second group selector is released, as has been described.

When sequence switch 510 opens contact 125 517 and in consequence relay 542 on the final selector is deenergized, the sequence switch 550 is energized over its contact 556 bottom and back contact of relay 542 and starts from its position 11, moving over positions 130

12 and 13 after which it continues the release, as has been described.

If a premature release is made during the progress of selection through the withdrawal of the plug on the outgoing end of the trunk, relay 233 is deenergized and in consequence relay 229. The sequence switch 206 is energized in the circuit over back contact of 229 as described, starts from position 10 and is moved into position 18. If the premature release happens at the time the second group selector is searching for the terminals of a free final selector, a relay 502 being deenergized, after opening of contact 214, causes the disconnection of the left hand high resistance winding of the test relay 513, and sequence switch 510 is energized in the circuit over its contact 521 top and back contact of relay 502 and advances over position 3 and 4 into position 5 in which the power magnet 530 being energized over the back contact of relay 512, continues to rotate the brush carriage without testing the terminals, until the brushes are restored to their position of rest and the home contact 523 is closed. Relay 512 is thereby energized in the circuit over the home contact 523, as has been described, the power magnet 530 is disconnected and sequence switch 510, together with the holding magnet 525 is energized, the brush carriage is arrested and the sequence switch 510 is started from its position 5. In position 6 the sequence switch 510 maintains its energization over back contact of relay 502 and moves into position 17.

The B operator is also enabled to force the release of a connection in exceptional cases, such for example when she desires to correct a mistake before the selection is completed and ringing current sent to the subscriber's station. To force the release the B operator depresses the assignment key 203 together with a common forced release key 360 shown in Fig. 2. Relay 247 in Fig. 1 is thereby energized in a circuit over conductor 394 and both keys mentioned and in closing its left hand contact maintains its operation also after the keys have been restored. On its right hand contact relay 247 prepares a circuit for the sequence switch 206 over sequence switch contact 248 top and the left hand contact of the assignment key. The sequence switch can therefore only start the release after the assignment key is freed, so that the trunk cannot be assigned a second time, which could otherwise happen if the assignment key remains depressed until the sequence switch reaches position 1. If the B operator undertakes a forced release during the time the sequence switch 206 is in position 2 and the sequence switch 251 is rotating searching for a free register with which a connection cannot be for some reason obtained, the sequence switch 206 is im-

mediately advanced into position 3 over the circuit as has been described, and is held in this position until sequence switch 251 reaches its position 13. The circuit for the energization of the sequence switch 206 is then closed over right front contact of relay 247, sequence switch contact 248 bottom and contact 252 bottom of sequence switch 251. This insures that the sequence switch 206 cannot pass over position 3 unless sequence switch 251 is arrested on the terminals of a free register or in a position in which no register can be connected so that when sequence switch 206 later passes over positions in which connections to the contacts of sequence switch 251 are made, these cannot disturb another connection with a register.

If for the purpose of obtaining a toll connection the local connection is forcibly released by connecting terminals 567 temporarily to ground, relay 572 is deenergized and the sequence switch 550 is energized in the circuit over its contact 581 top and back contact of relay 572. The sequence switch 550 moves over position 15 into position 16 and after the sequence switch contacts 575 and 576 are opened, relay 573 is deenergized and the clearing-out signal is transferred to the A operator's position as described. The sequence switch 550 of the final selector remains in position 16 until the connection is released on the A board, and when relay 542 is deenergized, as has been described, sequence switch 550 is energized in the circuit over the back contact of said relay and starts from position 16, completing the restoration of the final selector.

Assuming that during the time the A register is engaged on the progress of a selection the B operator depresses an assignment key of another trunk for the purpose of establishing a new connection, the sequence switch corresponding to sequence switch 251 would come to rest in one of its positions 2-5-8 or 11, establishing thereby a test circuit over relay 213 of the trunk, contact 258 of sequence switch 251 conductor 395 and relays 331 and 332 of the B register via contact 333 of its sequence switch 330, contact 321 of sequence switch 310 of the A register and contact 348 of sequence 340 of the C register. Relays 213 and 337 and 332 are energized and in consequence relay 336 which connects the battery to the circuit described making it independent of the sequence switch contacts 333 or 321. If now the register A becomes free and its contact 321 is opened, the circuit of the B register cannot be disturbed from the moment relay 336 has closed its front contact. As sequence switch 330 has left its position 1 the A register if it becomes free appears busy until sequence switch 330 reaches position 7 and its contact 335 is closed.

If the A and B registers are engaged 130

when the B operator depresses the assignment key of a new trunk, the sequence switch of this trunk corresponding to sequence switch 251 in Fig. 1 can stop itself in one of the positions 3—6—9 or 12, providing that the sequence switch contact 321 of sequence switch 310 of the A register is in one of its positions 7 to 18 and relay 349 is energized; and further that the sequence switch 330 is 10 in one of its positions 7 to 18 and its contact 335 is closed. The test relays 313 and 312 together with the relays 341 and 342 are thereby energized in a circuit containing contact 259 of sequence switch 251; conductor 396 contact 343 of sequence switch 340 of the C register, front contact of relay 341 and contact 335 of sequence switch 330. In positions 2 to 6 of sequence switch 340 the right hand winding of relay 349 is energized 15 20 in a circuit over sequence switch contact 345 and keeps on its back contacts the test circuits for the A and B registers opened.

What is claimed is:

1. In a telephone exchange system, a telephone line, an operator's position, a plurality of automatic switches, a trunk line leading from said position to said switches, manual switching means at the operator's position for connecting said telephone line 25 to the trunk line, a plurality of controlling mechanisms, means for associating one of said mechanisms with said trunk line, means controlled by said mechanism for selectively operating a portion of said switches to extend said trunk line, and means dependent upon the operation of said manual switching means for rendering said mechanism effective to control the selective operation of the remaining of said switches to further extend 30 35 40 said trunk line.

2. In a telephone exchange system, a telephone line, an operator's position, a plurality of automatic switches, a trunk line leading from said position to said switches, a plug and jack switch at the operator's position for connecting said telephone line to said trunk line, a plurality of controlling mechanisms, means for associating one of said mechanisms with said trunk line, means controlled by said mechanism for selectively operating a portion of said switches to extend said trunk line, and means dependent upon the insertion of said plug in the jack for rendering said mechanism effective to control the selective operation of the remaining of said switches to further extend 45 50 55 said trunk line.

3. In a telephone exchange system, a telephone line, an operator's position, a plurality of automatic switches, a trunk line leading from said position to said switches, a plug and jack switch at the operator's position for connecting said telephone line to the trunk line, a plurality of controlling 60 65 mechanisms, means for associating one of

said mechanisms with said trunk line, means controlled by said mechanism for selectively operating a portion only of said switches to extend said trunk line, and means dependent upon the insertion of said plug in the jack 70 for rendering said mechanism effective to control the selective operation of the remaining of said switches to further extend said trunk line.

4. In a telephone exchange system, a telephone line, an operator's position, a plurality of automatic switches, a trunk line leading from said position to said switches, a plug and jack switch at said position for connecting said telephone line to the trunk 75 80 line, a plurality of controlling mechanisms, means for associating one of said mechanisms with said trunk line, means controlled by said mechanism for selectively operating a portion of said switches to extend said trunk line independently of the insertion of said plug in the jack, and means dependent upon the insertion of said plug in the jack 85 for rendering said mechanism effective to control the selective operation of the remaining of said switches to further extend the said trunk line.

5. In a telephone exchange system, a telephone line, an A operator's position, a plurality of automatic switches, a trunk line leading from said position to said switches, a manual switching means at the operator's position for connecting said telephone line to said trunk line, a B operator's position, a plurality of controlling mechanisms at said 90 95 last position, means controlled by the B operator for associating one of said mechanisms with said trunk, means controlled by said mechanism for selectively operating a portion only of said switches to extend said 100 105 trunk line, and means dependent upon the operation of said manual switching means for rendering said mechanism effective to control the selective operation of the remaining of said switches to further extend said trunk line.

6. In a telephone exchange system, a telephone line, an operator's position, a plurality of automatic switches, a trunk line leading from said position to said switches, a plug and jack switch at the operator's position for connecting said telephone line to said trunk, a plurality of controlling mechanisms, means for associating an idle one of said mechanisms with said trunk, means controlled by said mechanism for selectively operating a portion of said switches to extend said trunk, and means dependent upon the insertion of said plug in the jack for enabling said mechanism to control the selective operation of the remaining of said switches to further extend said trunk, said last named means serving to cause the release of said switches when said plug is removed from the jack.

7. In a telephone exchange system, a line, an A operator's position, a plurality of automatic switches, a trunk leading from said position to said switches, a plug and jack switch at the operator's position for connecting said line to said trunk, a B operator's position, a plurality of controlling mechanisms at the B operator's position, means controlled by the B operator for associating one of said mechanisms with said trunk, means controlled by said mechanism for selectively operating a portion of said switches to extend said trunk, means dependent upon the insertion of said plug in the jack for enabling said mechanism to control the selective operation of the remaining of said switches to further extend said trunk, said last named means serving to cause the release of said switches when said plug is removed from the jack, and means controlled by the B operator for forcing the release of said switches regardless of the condition of the plug and jack switch.

8. In a telephone exchange system, a line, an A operator's position, a plurality of automatic switches, a trunk leading from said position to said switches, a plug and jack switch at the operator's position for connecting said line to said trunk, a B operator's position, a plurality of controlling mechanisms at the B operator's position, an assignment key controlled by the B operator for associating one of said mechanisms with said trunk, means controlled by such mechanism for selectively operating a portion of said switches to extend said trunk, means dependent upon the insertion of said plug in the jack for enabling said mechanism to control the selective operation of the remaining of said switches to further extend said trunk, said last named means serving to cause the release of said switches when said plug is removed from the jack, and means responsive to the operation of said assignment key for forcing the release of said switches regardless of the condition of the plug and jack switch.

9. In a telephone exchange system, a line, an A operator's position, a B operator's position, a plurality of trunks leading from the A operator's position to the B operator's position, a plug and jack switch at the A operator's position for connecting said line to one of said trunks, a plurality of automatic switches, a plurality of controlling mechanisms at the B operator's position, assignment keys each individual to one of said trunks for associating said mechanisms with said trunks, means controlled by a selected mechanism for selectively operating a portion of said switches to extend said trunks, means dependent upon the insertion of said plug in the jack for enabling such mechanism to control the selective operation of the remaining of said switches to further extend

said trunks, said last named means serving to cause the release of said switches when said plug is removed from the jack, a release key common to said plurality of trunks, and means responsive to the actuation of said release key and one of said assignment keys for releasing said switches regardless of the condition of the plug and jack switch. 70

10. In a telephone exchange system, a line, an A operator's position, a B operator's position, a plurality of trunks leading from the A operator's position to the B operator's position, a plug and jack switch at the A operator's position for connecting said line to one of said trunks, a plurality of automatic switches, a plurality of controlling mechanisms at the B operator's position, assignment keys each individual to one of said trunks for associating said mechanisms with said trunks, means controlled by such mechanism for selectively operating a portion of said switches to extend said trunk, means dependent upon the insertion of said plug in the jack for enabling such mechanism to control the selective operation of the remaining of said switches to further extend said trunk, said last named means serving to cause the release of said switches when said plug is removed from the jack, a releasing key common to said plurality of trunks, and means controlled by the actuation of said release key and one of said assignment keys for releasing said switches regardless of the condition of the plug and jack switch, said last mentioned means being effective to cause 100 release of said switches only after the assignment key has been depressed and been released. 95

11. In a telephone exchange system, a telephone line, an operator's position, an automatic switch, a trunk leading from the operator's position to said switch, a manual switch at the operator's position for connecting said telephone line to said trunk, a plurality of controlling mechanisms, means for associating one of said mechanisms with said trunk, means controlled by said mechanism for selectively operating said switch to extend said trunk, other automatic switches, a called line, means dependent upon the operation of said manual switch for rendering said mechanism effective to control the selective operation of said other automatic switches to extend said trunk to the called line, a signal at the operator's position, and means for operating said signal when the called line is found busy. 110 105 115

12. In a telephone exchange system, a telephone line, an operator's position, an automatic switch, an auxiliary switch having successive positions for controlling said automatic switch, a trunk leading from the operator's position to said automatic switch, a manual switch at the operator's position for connecting said telephone line to said 120 125 130

trunk, a plurality of controlling mechanisms, means for associating one of said mechanisms with said trunk, means controlled by said mechanism for selectively operating 5 said automatic switch to extend said trunk, other automatic switches, a called line, means dependent upon the operation of said manual switch for rendering said mechanism effective to control the selective operation 10 of said other automatic switches to extend said trunk to the called line, a signal at the operator's position, means for stopping said auxiliary switch in a signaling position when the called line is found busy, and means for 15 intermittently operating said signal when said auxiliary switch is in its signaling position.

13. In a telephone exchange system, a telephone line, an A operator's position, a B 20 operator's position, a trunk leading from one position to the other, a plug and jack switch at the A operator's position for connecting said line to said trunk, a plurality of

automatic switches, three register sets at the B operator's position, a set of number keys, 25 means for associating an idle register set with said trunk, means for associating the number keys with said register set, means controlled by said register set for selectively operating a portion of said switches to extend said trunk, and means dependent upon the insertion of said plug in the jack for rendering said register set effective to control the operation of the remaining of said 30 selective switches to further extend said trunk, said register sets being so arranged that the first set is always taken for use when idle, the second set being taken only when the first set is busy and the third set being taken only when the first and second sets are 35 busy, said register sets being further arranged such that none are available for use 40 while any one is associated with said key set.

In witness whereof, I hereunto subscribe my name this 11th day of July A. D., 1918. 45
LIPA POLINKOWSKY.
